(57) **CLAIM**

We claim the ornamental design for scraper panels for golf cart mat, as shown and described.

DESCRIPTION

FIG. 1 is a plan view of a golf cart mat incorporating our design;

FIG. 2 is a top perspective detail of FIG. 1, showing a left scraper panel;

FIG. 3 is a top view of the scraper panel shown in FIG. 2; FIG. 4 is a left side view of the scraper panel shown in FIG. 2;

FIG. 5 is a top perspective detail of FIG. 1, showing a right scraper panel that is a mirror image of the left scraper panel; FIG. 6 is a top view of the scraper panel shown in FIG. 5; FIG. 7 is a right side view of the scraper panel shown in FIG. 5;

FIG. 8 is a sectional view taken along Line 8-8 of FIG. 3; and,

FIG. 9 is a sectional view taken along Line 9-9 of FIG. 3. The bottom of the mat is unadorned and forms no portion of the claimed design. The broken lines shown illustrate environment that forms no part of the claimed design.
